UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

LOOSE-SHEET DEVICE.

1,288,342.

Specification of Letters Patent. Patented Dec. 17, 1918.

Application filed November 17, 1917. Serial No. 202,485.

To all whom it may concern:

Be it known that I, GEORGE P. WIGGINTON, a citizen of the United States, residing at the city and county of Kalamazoo, State 5 of Michigan, have invented certain new and useful Improvements in Loose-Sheet Devices, of which the following is a specification.

This invention relates to improvements in 10 loose sheet devices.

My improvements are especially designed to facilitate the handling of loose sheets, by which term I include cards and the like, in accounting or record systems.

15 The main objects of this invention are:

First, to provide an improved loose sheet device which facilitates the handling or manipulation of loose record sheets.

Second, to provide an improved loose 20 sheet device which facilitates the use of loose sheets in record and accounting systems and at the same time provides effective holders or files therefor.

Third, to provide an improved loose sheet 25 device including a file or holder which is of large capacity.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment 35 of my invention is clearly illustrated in the accompanying drawing, forming a part of this specification, in which:

Figure I is a perspective view of a cabinet containing a plurality of the holders 40 employed by me in my improved loose sheet devices.

Fig. II is a perspective view of one of the holders removed from the cabinet.

Fig. III is a perspective view of one of 45 my improved loose sheet devices opened, the removable sheet support being also shown.

Fig. IV is a vertical longitudinal section 50 on a line corresponding to line 4—4 of Fig. V with a part of the sheets disposed in each holder member, the sheet support being disposed in one member.

Fig. V is a detail section on a line corresponding to line 5—5 of Fig. VI, showing 55 a part of the sheets arranged in an offset relation.

Fig. VI is a detail section on a line corresponding to line 6—6 of Fig. V with the binder members in position.

Fig. VII is a transverse section on a line 60 corresponding to line 7—7 of Fig. II.

Fig. VIII is a perspective view of the binder member provided with posts.

Fig. IX is an enlarged detail side elevation 65 showing details of the connections for the holder members.

In the drawing similar reference characters refer to similar parts throughout the several views, and the sectional views are taken looking in the direction of the little arrows at the ends of the section lines.

Referring to the drawing, the sheets 1, illustrated, are provided with spaced notches 2 and holes 3, the sheets being such as are shown in my Patent #1,174,458, March 7, 1916. My present improvements are well 70 adapted for use in connection with sheets employed in accounting systems employing the sheets of that patent. The details of the sheets may, however, be very greatly varied as my present improvements are 75 adapted for use with a great variety of sheets and in a variety of relations.

In the structure illustrated I provide a holder comprising a pair of holder members designated generally by the numerals 4 and 85 5, each of these holder members comprising a bottom wall 6 and rear wall 7 disposed at right angles. The side walls 8 are tapered forwardly from the rear walls so that they are complementary when the members are 80 superimposed or disposed in a reversed facing relation, as shown in Fig. II. When thus disposed they provide a rectangular box or container.

In the structure illustrated the rear wall 95 of the holder 5 has pins 9 projecting from its ends with which the notches 10 in the front ends of the side walls of the holder 4 may be engaged.

The bottom wall of the holder 5 has a keeper 11, while the rear wall of the holder 4 has a latch 12, preferably operated by means of a key, so that the members are locked in their closed position and may be handled as a file box and placed in a cabinet, 100 105 as 13,—see Fig. I.

To facilitate the fingering of the sheets I provide the tapered support 14 which may be placed in one of the holder members at the rear of the sheets, as shown in Fig. IV, 110

supporting the sheets at an acute angle to the rear wall of the holder and thereby supporting their upper edges in a stepped relation as shown in the drawing. This support feature is described in detail and claimed in my copending application, Ser. No. 146,761, filed Feb. 5, 1917.

These holder members, when separated, constitute means for supporting the sheets so that they may be conveniently transferred from one to the other, which is a matter of great convenience in the manipulation of the sheets in accounting systems. A convenient means for accomplishing this is a support comprising side members 16 connected by cross pieces 17 and 18, the upper edges of the side members having V-shaped recesses therein constituting rests for the holder members so that they may be arranged there-in in with their rear walls adjacent, as shown in the accompanying drawing.

With the holder members thus supported the sheets may be conveniently manipulated or transferred from one to the other.

25. To facilitate alining the sheets the rear walls are provided with guide members 19 with which the notches in the sheets may be engaged, as shown in Fig. V.

The holder members are preferably of such width as to permit selected sheets being arranged in an offset relation to indicate a selected group or classification.

To facilitate the handling of the sheets as a unit and to better keep them in position when adjusted for storage or transportation I provide binding means comprising the binding member 20 having posts 21 thereon adapted to be inserted through alined holes 3. The binder member 23 is provided with spring clutches 24 adapted to engage the posts. To facilitate the releasing of the sheets the bottom of the holder member 4 has an opening 25 therein through which the binder member 20 and the posts 45 may be removed.

To facilitate the engaging of the posts the bottom of the holder member 5 has holes 26 therein positioned so that the posts may pass through the holes as shown in Fig. VI.

50. The binder member 20 has a notch 27 on each side adapted to coact with the guides 19 facilitating the insertion of the posts and also allowing the edges of the sheets to abut the rear wall. The binder member 23 has 55 a notch 28 therein also adapted to engage the guides.

By thus arranging the parts I provide a structure which greatly facilitates the manipulation of the sheets, is of large capacity and well adapted as a file or cabinet unit.

I have illustrated and described my improvements in one form in which I have embodied the same in practice. I have not attempted to illustrate or describe certain 65 modifications or adaptations which I con-

template as I believe the disclosure made will enable those skilled in the art to which my invention relates to embody or adapt the same as may be desired or as the particular use may render most adaptable.

Having thus described my invention, what I claim as new and desire to secure by Letters Patent, is:

1. The combination with loose sheets having notches open at their inner edges and holes adjacent their inner edges, of holder members each comprising bottom and rear walls and complementary side walls arranged so that the members may be superimposed in a reversed relation with the side walls edge to edge, one holder member having pins on the ends of its rear wall and a keeper on the inner side of its bottom wall, the other holder member having notches in the forward ends of its side walls adapted to engage said pins and a latch on its rear wall adapted to coact with said keeper when the holder members are reversed and superimposed, a support adapted to support said holder members so that the sheets may be transferred from one member to the other, a sheet and binder member guide on the rear wall of one of said holder members, and disengageable sheet binding means comprising a binder member adapted to engage said 95 guide.

2. The combination with loose sheets, of holder members each comprising bottom and rear walls and complementary side walls arranged so that the members may be superimposed in a reversed relation with the side walls edge to edge, one holder member having pins on the ends of its rear wall and a keeper on the inner side of its bottom wall, the other holder member having notches in the forward ends of its side walls adapted to engage said pins and a latch on its rear wall adapted to coact with said keeper when the holder members are reversed and superimposed, a support adapted to support said holder members so that the sheets may be transferred from one member to the other.

3. The combination with loose sheets having notches open at their inner edges and holes adjacent their inner edges, of holder members each comprising bottom and rear walls adapted to be disposed in a reversed facing relation, means for detachably securing said members together in such relation, sheet and binder member guides on the rear walls of said holder members and binder members notched to engage said guides, one binder member being provided with a post and the other with post engaging means, the bottom wall of one holder member having an opening therein permitting the removal therethrough of the binder member provided with the post and the bottom wall of the other member having a hole positioned to receive the post when engaged with the 130

sheets, and a support adapted to support the holder members so that the sheets may be transferred from one holder member to the other.

5. 4. The combination with loose sheets having notches at their inner edges and holes adjacent their inner edges, of holder members each comprising bottom and rear walls adapted to be disposed in a reversed facing 10 relation, means for detachably securing said members together in such relation, sheet and binder member guides on the rear walls of said holder members and binder members notched to engage said guides, one binder member being provided with a post and the other with post engaging means, the bottom wall of one holder member having an opening therein permitting the removal therethrough of the binder member provided 15 with the post and the bottom wall of the outer member having a hole positioned to receive the post when engaged with the sheets.

5. The combination with loose sheets having notches open at their inner edges and holes adjacent their inner edges, of holder members each comprising bottom and rear walls adapted to be disposed in reversed facing relation, means for detachably securing 20 said members together in such relation, sheet and binder member guides on the rear walls of said holder members and binder members notched to engage said guides, and a support adapted to support the holder 25 members so that the sheets may be transferred from one holder member to the other.

6. The combination with loose sheets having notches open at their inner edges and holes adjacent their inner edges, of holder 30 members each comprising bottom and rear walls adapted to be disposed in a reversed facing relation, means for detachably securing said members together in such relation, and sheet and binder member guides on the 35 rear walls of said holder members and binder members notched to engage said guides.

7. The combination with loose sheets having notches open at their inner edges and 40 holes adjacent their inner edges, of holder members each comprising bottom and rear walls adapted to be disposed in a reversed facing relation, means for detachably securing said members together in such relation, a support adapted to support said 45 holder members so that the sheets may be transferred from one member to the other, a guide on the rear wall of one of said holder members, and disengageable sheet binding 50 means comprising a binder member adapted 55 to engage said guide and a post, the bottom wall of one holder member having an opening 60 therein permitting the removal therethrough of the binder member provided with the post and the bottom wall of the other member having a hole positioned to receive the 65 post when engaged with the sheets.

to receive the post when engaged with the sheets.

8. The combination with loose sheets, of holder members each comprising bottom and rear walls adapted to be disposed in a reversed facing relation, means for detachably securing said members together in such relation, a support adapted to support said holder members so that the sheets may be transferred from one member to the other, and disengageable sheet binding means.

9. The combination with loose sheets, of holder members each comprising bottom and rear walls adapted to be disposed in a reversed facing relation, means for detachably securing said members together in such relation, a support adapted to support said holder members so that the sheets may be transferred from one member to the other.

10. The combination with loose sheets having notches open at their inner edges and holes adjacent their inner edges, of holder members each comprising bottom and rear walls arranged so that the members may be disposed in a reversed facing relation, means for detachably connecting said members in such relation, a sheet and binder member guide on the rear wall of one of said holder members, and disengageable sheet binding means comprising a binder member adapted 95 to engage said guide and a post, the bottom wall of one holder member having an opening therein adapted to permit the removal of the post therethrough, and the other bottom wall having a hole positioned to receive 100 the post when engaged with the sheets.

11. The combination with loose sheets, of holder members each comprising bottom and rear walls arranged so that the members may be disposed in a reversed facing relation, means for detachably connecting said members in such relation, a sheet guide on the rear wall of one of said holder members, and disengageable sheet binding means.

12. The combination of holder members each comprising bottom and rear walls adapted to be disposed in a reversed facing relation, means for detachably securing said members in such relation, sheet and binder member guides on the rear walls of said holder members and binder members notched to engage said guides, one binder member being provided with a post and the other with post engaging means, the bottom wall of one holder member having an opening 110 therein permitting the removal therethrough of the binder member provided with the post and the bottom wall of the other member having a hole positioned to receive the post when engaged with the sheets.

13. The combination of holder members each comprising bottom and rear walls adapted to be disposed in a reversed facing relation, means for detachably securing said members in such relation, and binder mem- 130

- bers, one binder member being provided with a post and the other with post engaging means, the bottom wall of one holder member having an opening therein permitting the removal therethrough of the binder member provided with the post and the bottom wall of the other member having a hole positioned to receive the post when engaged with the sheets.
- 10 14. The combination of holder members each comprising bottom and rear walls adapted to be disposed in a reversed facing relation, means for detachably securing said members together, a guide on the rear wall of one of said holder members and binding means comprising a binder member adapted to engage said guide, and a post, the bottom wall of one holder member having an opening therein permitting the removal of the post therethrough and the bottom wall of the other member having a hole positioned to receive the post when engaged with the sheets.
- 15 15. The combination of holder members each comprising bottom and rear walls adapted to be disposed in a reversed facing relation, means for detachably securing said members together, a guide on the rear wall of one of said holder members and binding means comprising a binder member adapted to engage said guide and a post, the bottom wall of one holder member having an opening therein permitting the removal of the post therethrough.
- 20 16. The combination of holder members each comprising bottom and rear walls adapted to be disposed in a reversed facing relation, means for detachably securing said members together, and binding means comprising a binder member and a post, the bottom wall of one holder member having an opening therein permitting the removal of the post therethrough and the bottom wall of the other member having a hole positioned to receive the post when engaged with the sheets.
- 25 17. The combination of holder members each comprising bottom and rear walls adapted to be disposed in a reversed facing relation, means for detachably securing said members together, and binding means comprising a binder member and a post, the bottom wall of one holder member having an opening therein permitting the removal of the post therethrough.
- 30 18. The combination of holder members each comprising bottom and rear walls and complementary side walls tapered from the rear walls so that the members may be superimposed in a reversed relation with the side edge to edge, pins on the ends of one rear wall and a keeper on the inner side of one bottom wall, the other holder member having notches in the forward ends of its side walls adapted to engage said pins and a latch on its rear wall adapted to coact with said keeper when the holder members are reversed and disposed facing.
- 35 19. The combination of holder members each comprising bottom and rear walls and complementary side walls tapered from the rear walls so that the members may be disposed in a reversed facing relation with the side walls edge to edge, means for detachably connecting said members, and a support comprising rests disposed so that said holder members may be arranged in the rests in an opposed relation with their rear walls adjacent.
- 40 20. The combination with loose sheets, of holder members each comprising bottom and rear walls and complementary side walls arranged so that the members may be superimposed in a reversed facing relation with their side walls edge to edge to inclose the sheets or said holder members may be separated and disposed with their rear walls adjacent and the sheets arranged in either with their ends abutting the rear walls and transferred from one holder member to the other, and means for detachably connecting said members in their superimposed relation.
- 45 21. The combination of holder members each comprising bottom and rear walls adapted to be disposed in a reversed facing relation, means for detachably securing said members together, and a support comprising a pair of rests disposed so that said holder members may be arranged in the rests in an opposed relation with their rear walls adjacent and sheets transferred from one member to the other.
- 50 22. The combination of holder members each comprising bottom and rear walls adapted to be disposed in a reversed facing relation, means for detachably securing said members together, and a support adapted to support said members when separated so that the sheets may be transferred from one member to the other.
- 55 In witness whereof, I have hereunto set my hand and seal in the presence of two witnesses.
